(57) **CLAIM**

The ornamental design for a mass spectrometer, as shown and described.

DESCRIPTION

FIG. 1 is a front perspective view of a mass spectrometer showing our new design;

FIG. 2 is a front view thereof;

FIG. 3 is an enlarged view of portion 3 of FIG. 2;

FIG. 4 is a rear view of the mass spectrometer shown in FIG. 1;

FIG. 5 is a left side view thereof;

FIG. 6 is a right side view thereof;

FIG. 7 is a top view thereof; and,

FIG. 8 is a bottom view thereof.

The broken lines shown are included for the purpose of illustrating portions of the mass spectrometer that form no part of the claimed design.
